UNITED STATES PATENT OFFICE

WILLIAM A. DUNCAN, OF COVINGTON, KENTUCKY

MACHINE FOR WELDING FLUES

Application filed February 26, 1926. Serial No. 90,883.

The object of this invention is to provide, in a machine of the type specified, a particular form of mandrel and rolls for reducing, opening, and scarfing flues which have become defective, and welding thereto an end section, or safety end, for the purpose of restoring to serviceable condition a boiler flue or superheater flue.

A further object is to provide particular means for reducing the end portions of new tubes or flues.

With the foregoing and other objects in view, the invention consists in the novel construction and arrangement of elements described, illustrated and claimed, it being understood that modifications may be made in the scope of the claims, without departing from the spirit of the invention.

In the drawings forming part of this application,

Figure 1 is a view of the machine to which the mandrel of special form, and the cooperating rolls of particular type are applied, the view being in elevation.

Figure 2 is an elevation of the structure of Figure 1 from another angle.

Figure 3 is a section longitudinally of the mandrel and the rolls, a fragmentary portion of a new flue to be reduced being illustrated.

Figure 4 is a view similar to Figure 3, the mandrel and rolls being designed, however, for operating upon old flues to be reclaimed.

Figure 5 is a fragmentary view in section, with parts in elevation, and showing a flue having an end portion longer than that illustrated in Figure 4.

Figure 6 is a view in section and elevation, showing the use of washers between the rolls and an element on which the axial members of the rolls are mounted, this arrangement permitting the rolls to be properly positioned with reference to the joint to be welded.

Figure 7 is a view similar to Figure 6, but showing a single washer at each end of the roll, in order to place the latter in the position desired with reference to the weld.

Figure 8 shows one of the rolls in elevation, this roll having a long cylindrical portion.

Figure 9 shows two sizes of rolls, in which the cylindrical portions are shorter than in Figure 8.

Figure 10 is an elevation of the end portion of a new tube, reduced as required. 55

Figure 11 is a view in elevation, with a portion broken away, showing the end of a tube which has been reduced and scarfed, the tube being shorter than the tube of Figure 10, because of the necessity of cutting off 60 a defective end portion.

Figure 12 is a view in elevation showing a welded joint, in full lines, a safety end portion having been welded on to the reclaimed tube, this figure also showing, in dotted lines, the position at which a cut would have to be made subsequently if the tube is to be reconditioned a second time.

In Figures 1, 2 and 3, I have illustrated the essential features of a machine of standard construction, such as that disclosed in U. S. Patent No. 633,136, issued September 19, 1899, this machine being illustrated, in the present case as being provided with the particular mandrel and rolls forming the subject matter of the case under consideration. 70

A foot lever 10 controls a lever or levers 11, through connections 12 and 13, and the lever or levers 11 control a slidably collar 15 to which arms 16 are connected by links or the like designated 17. The arms 16 are pivoted at 18, and carry devices mounting the rolls having cooperation with the mandrel. 80

A bracket 20 is provided with a slot 21, through which a bolt or pin 22 passes, this element 22 also passing through a slide 23, which is vertically adjustable by means of the screw 24, a particular adjustment being maintained by nut and washer 25 and 26 carried by bolt or pin 22 and adapted to engage the surface of element 20. The slide 23 carries a pin or bolt 28 constituting the axial element of each roll 30; a nut 31 received in

recess 32, and engaging the bolt serving to retain the roll. The several rolls include cylindrical portions 33, the length of which depends upon the use to which the roll is to be put. The roll further includes a tapered portion 34.

The assembly of Figure 3 is designed for 100

reducing new flues, it being unnecessary to add or weld on any end section or "safety end", as in other cases to be described. The mandrel is tapered at its outer end, this element being designated 35, and being carried by an axial member 36 engaged by a nut 37. The reduced end of the mandrel permits of easy and prompt withdrawal of the flue, after it has been reduced. The flue being operated upon and constituting the work is designated 38, and the reduced portion is shown at 39, the portion 40 being cylindrical and constituting the end of the flue. End portion 40 engages a flange or collar 41 on the end of the mandrel, constituting a stop, and forming an important feature of the construction. A tapered portion 44 provides for opening and scarfing the end 45 of the tube so that an end section may be welded thereto, and the rolls 30' of Figures 4 and 5 are shown as operating upon tubes in which the reduced end portions are of different lengths. Washers 47 and 48 are mounted at the outer end of bolt or pin 49, and serve as spacing devices for retaining rollers 30' in the position indicated in the joint to be welded. In Figures 6 these washers 47 and 48 have been moved to position at the opposite end of rollers 30', so that the nut 49' engages the body portion of said rollers, this arrangement being employed when an end or "safety end" 44' is to be welded onto the ends of the tube. In Figure 7, the washers 47 and 48 are positioned at opposite ends of the roller 30', the "safety end" being shorter than in Figure 6.

Figures 8 and 9 illustrate rollers of different sizes or lengths adapted for performing different operations. Figure 10 shows the reduced end 50 of a new tube 51, the reduction having been effected on a machine carrying rollers and a mandrel of the kind herein described. Figure 11 shows a tube 52 having a reduced and scarfed end 53, and Figure 12 shows a "safety end" 54 welded at 55 to the reduced end of a tube 56. This view also shows in dotted lines, where the weld will be made in the event that the tube is shortened when reconditioned a second time.

It may be added that the mandrel 35 is advanced and retracted in the standard machine disclosed by means of lever 60 which indirectly imparts slidable movement to element 61, and a vertical element 62 connected therewith for operating a yoke, member 63, imparting thrust to the axial member of the mandrel.

Having thus described the invention, what is claimed as new, is:

1. A device of the character described including a centrally arranged non-movable support and a plurality of movable supports arranged about the non-movable support, a mandrel mounted on said non-movable support to receive a tube thereon and having elongated cylindrical and tapered portions

merging into each other intermediate the ends of said mandrel, rolls removably mounted on the movable supports and having cylindrical and tapered portions merging into each other intermediate the ends thereof and of shorter lengths than the portions of the mandrel, and spacing elements interchangeable from one end of each movable support to the other end thereof to vary the positions of the rolls endwise relatively to the mandrel and thereby vary the cylindrical and tapered portions of said rolls relative to the cylindrical and tapered portions of the said mandrel.

2. A device of the character set forth comprising a fixed mandrel, a plurality of movable supports, rolls removably mounted on said supports to restrict a tube on the fixed mandrel, a flange at one end of the fixed mandrel, an inclined shoulder on the fixed mandrel adjacent the flange to cooperate with the latter to scarf the end of a tube when compressed by the rolls, and spacing elements interchangeable from the ends of the support to the other end thereof to adjust the rolls towards and from the flange and shoulder.

In testimony whereof I affix my signature.

WILLIAM A. DUNCAN.
